PAGE 2

Fig. 2

I claim:
The ornamental design for a combination food warmer and dispenser, substantially as shown.
